J. GOULBOURN ET AL

MACHINE FOR OPERATING UPON BOOTS AND SHOES

Original Filed Feb. 3, 1921

UNITED STATES PATENT OFFICE.

JOSEPH GOULDBOURN AND FRED RICKS, OF LEICESTER, ENGLAND, ASSIGNEES TO
UNITED SHOE MACHINERY CORPORATION, OF PATERSON, NEW JERSEY, A COR-
PORATION OF NEW JERSEY.

MACHINE FOR OPERATING UPON BOOTS AND SHOES.

Original application filed February 3, 1921, Serial No. 442,040, and in Great Britain February 16, 1920.
Divided and this application filed February 3, 1923. Serial No. 617,737.

The present invention relates to machines for operating upon boots and shoes and more particularly to the type of machine disclosed in the patent to Bates, No. 1,140,349, of May 5 25, 1915.

This application is a division of the application of Gouldbourn and Ricks, Serial No. 442,040, filed Feb. 3, 1921.

The above mentioned Bates patent discloses a machine for operating upon boots and shoes which is provided with means for varying the speed of operation as the different parts of the boot or shoe are brought into operative position. The specific form of the apparatus shown in the patent is designed for operating upon the soles of shoes which are held upon a horn of the usual form in such a manner that the operations carried out at the toe of the sole are 20 performed at a slower rate than the operations upon the straight parts of the sole, these variations in speed being automatically effected through the rotation of the horn.

The object of the present invention is to provide improvements in machines of this general nature in order to allow the operator to vary the general speed of operation at will, while still maintaining the automatic variations in speed as the different parts of 30 the shoe are brought into operative position.

With this object in view, a feature of the invention contemplates the provision of means for operating upon a boot or shoe, together with means for automatically controlling the speed of said operating means as different portions of the boot or shoe are brought into operative position, and means under the control of the operator for controlling the general speed of operation, at the 40 same time allowing the automatic speed controlling means to function in its usual manner. This permits the operator conveniently to vary the speed of operation for different conditions of work and allows him to take 45 advantage of all opportunities to speed up the machine without injuring the quality of the product.

Other features of invention consist in certain novel features of construction, combinations and arrangements of parts hereinafter

described and claimed, the advantages of which will be apparent to those skilled in the art from the following description.

The accompanying drawing illustrates a machine embodying the several features of 55 the invention.

The illustrated embodiment of the invention comprises a machine for carrying out the McKay method of stitching the soles of boots and shoes to the uppers, and includes 60 a horn of the usual type adapted to be received within the shoe, together with needle, presser foot and feed point mechanisms to perform the necessary stitching operations. The horn is rotatable upon the machine 65 frame and is connected with a cam which serves to control a variable speed gearing as the horn is rotated into various angular positions. A clutch mechanism with a co-operating treadle is provided to connect and 70 disconnect the machine from the source of power and also means are provided whereby continued motion of the treadle after engagement of the clutch mechanism acts on the variable speed mechanism to change the 75 general speed of operation of the machine.

Referring particularly to the drawing, the machine column 1 has mounted thereon a rotatable horn 3 of the usual form. The whirl contained within the horn is actuated 80 through gears 5 and 7 and shaft 9 from the cam shaft of the machine and the needle, feed point and presser foot mechanisms are also actuated from the cam shaft in the manner fully described in application Serial No. 442,040, above referred to. The presser foot assembly is indicated generally at 10 in a position opposite the upper part of the horn. Rotatable with the horn is a cam 12 which has bearing against its periphery a cam roll 85 14 mounted upon a bell crank lever 16 which is connected with one arm of a second bell crank lever 18 by a rod 20. The bell crank lever 18 is pivoted at 19 and its other arm connects by a rod 22 with the variable speed mechanism to be presently described in detail. The rod 22 is preferably provided with a turn buckle 24 to allow of convenient adjustment for length. With this construction 95 the variable speed mechanism is controlled 100

in accordance with the variations in periphery of the cam 12 as the horn 3 is rotated into various angular positions.

The desired control of the general speed 5 of the machine by the operator is carried out through the action of a rod 26 which is adapted to rise upon the depression of a foot treadle (not shown). To this end, the pivot 19 of the bell crank lever 18 is not 10 stationary but is connected with a lever 28 which is itself pivoted to the frame of the machine at 30. A spring 32 is connected between the lever 28 and the upper arm of the bell crank lever 18 in order to urge the 15 rod 20 to the left and hold the cam roll 14 in engagement with the cam 12 in all positions. A second spring 34 is connected between the lever 28 and the fixed part of the machine to hold the lever normally against 20 a stop 36. The clutch rod 26 passes through a projecting ear 38 of the lever 28 and is provided with a shoulder 40 which is adapted to engage the ear after the rod 26 has been lifted sufficiently to start the machine 25 by actuation of the clutch mechanism. Upon engagement of the shoulder 40 with the ear 38 the lever 28 is raised, thereby lifting the bell crank lever 18 bodily and also raising the control rod 22 to act on the variable 30 speed mechanism. This actuation of the variable speed mechanism in no way interferes with the control of the mechanism through the action of the cam 12, the latter serving to vary the speed of operation, as 35 before, as different parts of the boot or shoe are being operated upon.

The clutch mechanism and the variable speed mechanism may be of any desired form but the former is preferably of the 40 type disclosed in the patent to Jerram, No. 1,124,620. The upper part of the clutch rod 26 is connected to a bell crank lever 42 which is pivoted upon the machine head and which has one arm pivoted to the link by which 45 the clutch illustrated and described in the above Jerram patent is controlled. The downward movement of the rod 26 is limited by a stop screw 44 attached to the bell crank and arranged to engage a face on the 50 machine. The clutch is designed and arranged to be thrown into operation by the upward movement of the rod before the shoulder 40 engages the ear 38 after which continued movement of the rod 26 lifts the lever 28 55 to vary the speed of the machine. A casing 46 is mounted upon the rear of the machine to which casing is attached the rear face 48 of a brake disk against which the front face of a clutch cone 50 of the clutch may engage 60 to stop the machine. The main shaft 52 of the machine projects through the casing and is provided with a sleeve 53 which is confined between collars 55 at its ends. Mounted upon the sleeve 53 is a second sleeve 56 65 to which the hub of the driving pulley 58

is splined. A third sleeve 60 is mounted upon sleeve 53 at the left of sleeve 56 and has splined thereon the clutch member 62 of the clutch. The sleeves 56 and 60 are connected by roller clutch members 64 and 70 are each provided with integral gears 66 and 68, respectively, the former being somewhat larger than the latter. The gears mesh with pinions 70 and 72 which are fast upon a shaft 74 journaled for rotation within a 75 brake drum 76 which has hub portions 78 and 80 mounted on the sleeves 56 and 60. The brake drum 76 is urged toward the clutch member 62 by springs 82 which bear between the inner surfaces of the pulley 58 80 and the brake drum. The left hand collar 55 is acted upon by suitable springs (not shown) which tend to force the sleeve 53 to the right, this tendency being opposed by a hand cam lever 84 mounted upon the shaft. 85 When the cam lever is moved to the position indicated in dotted lines, the sleeve is caused to move toward the right and the clutch member 62 thus moves out of the range of clutch cone 50 and it then becomes impossible to start the machine by power. However, upon depression of the treadle to partially raise the rod 26 to separate the clutch member 50 from the brake member 48, the machine may be turned over by hand by 90 means of a hand wheel 4 attached to the main shaft.

The brake drum cooperates with a pair of brake shoes 86 which depend from a bracket on the casing 46. The lower ends of the shoes are connected by a toggle 88 which is connected to one end of an arm 90 fast on a horizontal rock shaft 92 which is parallel to the main shaft 52. The shaft 92 is connected by a suitable lever with the upper end of the rod 22 in such a manner that raising of the rod causes application of the brake shoes to the brake drum. The contacting surfaces of the brake drum 76 and shoes 86 are bevelled so that as the shoes 100 grasp the drum they wedge it towards the rear end of the shaft and away from the end face of the cone member of the clutch with which it is held in driving contact by the springs 82 while the drum and the cone member are rotating at the same speed.

It will be seen that when the brake drum is allowed to freely rotate, the entire assembly including the driving pulley, the brake drum and the clutch member 62 will all rotate at the same velocity. However, if the brake drum is retarded in its motion, the rotation of the pulley 58 is transmitted to the clutch member 62 through the train of pinions and gears, the speed taken by the member 62 being dependent upon the gear ratio and upon the braking effect applied to the drum. The maximum speed of the clutch member 62 occurs when the brake drum is stationary.

In order to start the machine, the operator depresses the treadle slightly, thus lifting the rod 26 and bringing the clutch members 50 and 62 into engagement as explained in the patent to Jerram, above referred to, at the same time releasing the member 50 from the brake member 48. The machine will now operate in accordance with variations in the periphery of the cam 12, the speed 10 being caused to change through the rising and falling of the rod 22 in applying varying degrees of brake pressure upon the brake drum. Furthermore, the operator may vary the general speed of operation by depressing the treadle to further raise the clutch rod 26 which also lifts the lever 28 carrying with it the bell crank lever 18 and the rod 22.

While it is preferred to employ the specific construction and arrangements of parts shown and described, it will be understood that this construction and arrangement is not essential except so far as specified in the claims and may be changed or modified 25 without departing from the broader features of the invention.

The invention having been described, what is claimed is:

1. A machine of the class described having, in combination, means for operating upon a boot or shoe, a work support arranged to turn as successive portions of the work are presented to said operating means, mechanism for varying the speed of operation of said operating means, a cam arranged to turn with said work support, means operated from said cam for controlling said mechanism to vary the speed of operation of said operating means, and 30 means under the control of the operator for controlling said mechanism to vary the speed of operation of said operating means while said mechanism remains under the control of said cam.

2. A machine of the class described having, in combination, means for operating upon a boot or shoe, mechanism for varying the speed of operation of said operating means, means for automatically controlling said mechanism to vary the speed of operation as different portions of the boot or shoe are presented to the operating means, and means under the control of the operator for controlling said mechanism to vary the general speed of operation while said mechanism remains under the control of said automatic controlling means. 45

3. A machine of the class described having, in combination, means for operating upon a boot or shoe, mechanism for varying the speed of operation of said operating means comprising a lever pivotally movable to vary the speed of operation and bodily movable to vary the speed of operation, means for pivotally moving the lever automatically to vary the speed of operation as different portions of the boot or shoe are presented to the operating means, and means under the control of the operator for bodily moving the lever. 50

4. A machine of the class described having, in combination, means for operating upon a boot or shoe, mechanism for varying the speed of operation of said operating means comprising a lever pivotally movable to vary the speed of operation and bodily movable to vary the speed of operation, a work support arranged to turn as successive portions of the work are presented to said operating means, connections between the work support and lever for pivotally moving the lever to vary the speed of operation as different portions of the boot or shoe are presented to the operating means, and means under the control of the operator for bodily moving the lever. 55
